FUEL ADMISSION DEVICE FOR INTERNAL-
COMBUSTION ENGINES

Arthur Sandhofer, Cisco, Tex., assignor to Phillips Petroleum Company, a corporation of Delaware

Application August 28, 1941, Serial No. 408,672

4 Claims. (Cl. 137—153)

This invention relates to internal combustion engines and in its more specific aspects to improvements in fluid fuel admission means for internal combustion engines; and is a continuation-in-part of my prior filed application, Serial No. 353,941, filed August 23, 1940.

Heretofore, it has generally been the practice in the operation of two cycle engines to introduce the fluid fuel under pressure into the head end of the cylinder during the compression stroke of the piston by means of a fuel injector which includes a valve, a valve stem and a spring. The valve is opened through its cooperation with a rocker arm and a push rod or valve shaft, the latter being actuated by a geared connection to the crank end of the engine. After the fuel has been introduced into the cylinder, the above mentioned spring tends to close the valve. The "timing" (opening and closing) of the valve is controlled by a cam which operates one end of the rocker arm at predetermined intervals to open and close the valve.

The present invention is an improvement over the invention disclosed in the copending patent application of Jim Barton, inventor, Serial No. 269,777; and contemplates the admission of fuel into the head end of an internal combustion engine cylinder by means of a device which comprises a fuel valve, a valve stem, a spring, and a diaphragm or other form of movable partition, cooperatively arranged with respect to a plurality of control valves so that the fuel valve is operated by the alternate pressure and vacuum created behind the piston during the expansion and compression strokes of the piston. A small bore conduit places my device in communication with the back end of the engine cylinder; and, as the piston moves forward in each compression stroke, a partial vacuum is created behind the piston and also in my device. When the piston moves toward the back end of the cylinder on each expansion stroke, a pressure is produced in the conduit, which pressure is utilized to actuate the diaphragm to open the valve and admit fuel into the cylinder. I am able to accurately control the point in the engine cycle at which the fuel admission valve is alternately opened and closed in order to obtain optimum fuel economy and operating results by employing a simple, dependable and trouble-free device instead of by means of the complicated troublesome mechanism that was used in the past. The practice of my invention eliminates the conventional rocker arm, push

rod, cam and gear arrangement, and effects a number of advantages which will be readily understood by those skilled in the art on a perusal of the accompanying drawings in conjunction with the detailed description hereinafter presented.

It is the primary object of this invention to provide a fuel admission device which is adapted to increase the power delivered by internal combustion engines.

Another object of this invention is to provide a device of the character indicated which will effectively and efficiently control the admission of fuel into an internal combustion engine so that the engine may be operated under various load conditions at economical fuel consumption.

A third object of my invention is to provide a fuel admission device which is operable in a positive and dependable manner by alternate pressures and vacua created behind the piston of an internal combustion engine during the expansion and compression strokes of the piston.

This invention has for a further object the provision of an internal combustion engine fuel admission device which is simple in design, rugged in construction and relatively inexpensive to manufacture. By virtue of the simplicity of my design and the few moving parts that are subject to wear, the maintenance and replacement costs are reduced to a minimum.

A still further object of this invention is to provide a fuel admission device which is adapted to be readily substituted for other devices that are employed for the same purpose. This conversion may be quickly and inexpensively accomplished at the place of use, thereby avoiding costly delays which would result if the entire engine has to be returned to the factory or transported to a workshop which is especially equipped to make the conversion.

These as well as additional objects and advantages will be apparent by reference to the following specification and annexed drawings which respectively describe and illustrate preferred embodiments of my invention, and wherein

Figure 1 is a longitudinal cross section view through the center of an internal combustion engine cylinder having my invention operatively connected thereto;

Figure 2 is an enlarged elevation view of one embodiment of the invention, partly in cross section;

Figure 3 is an enlarged view of a portion of another embodiment of the invention, partly in cross section; and

Figure 4 is a fragmentary view of the casing in enlargement, and illustrates a preferred type of check valve arrangement in detail.

Referring to the drawings and more particularly to Figure 1, I have denoted therein an internal combustion engine cylinder 10, which is provided with the usual water-jacket 11 and is rigidly supported on an engine frame 12 by means of bolts 13. A piston 14 reciprocates within the cylinder and is connected to a piston rod 15 which passes through a packing gland 16 in the back end of the cylinder. A conventional spark plug 17 and air starting valve 18 are indicated at the head end of the cylinder. Air for normally operating the engine is introduced from the outside into an air inlet passageway 19, passes through air inlet valves 20 and chamber 21, and thence is admitted into the cylinder by way of inlet ports 22 and 23. The products of combustion are emitted from the cylinder by way of exhaust ports 24 and an exhaust outlet 25 communicating therewith.

Figure 2 illustrates a body member, generally indicated by reference numeral 26 and including a base member 27, a pair of supports 28, a valve actuating chamber 29, and a fluid chamber 30 having a cover plate 31, all assembled into a unitary structure by any suitable means known in the art. Base member 27 embraces a fuel chamber 32 that is provided with a tapped fuel inlet opening 33 for connection to a source of fuel supply (not shown), and is securely mounted to the head end of the cylinder so that a seat 34 for a fuel valve 35 is substantially flush with the inner surface of the cylinder head, as shown in Figure 1. Valve 35 has a stem 36 slidable in a guide 37 in fuel compartment 32 and extending through a conventional type of packing unit 38, consisting of a packing nut 39, a follower ring 40, and packing material 41. Valve stem 36 is threaded to engage with corresponding internal threads in a boss 42 that is integral with a diaphragm plate 43. A spider 44 supports a compression spring 45 that is concentrically disposed with respect to the valve stem for urging diaphragm plate 43 and valve stem 36 toward the left to normally maintain fuel valve 35 in closed position. As will be apparent from an inspection of Figure 2, compression spring 45 is also adapted to urge a diaphragm 46, which constitutes the lower wall of valve actuating chamber 29, toward the left. Reference numeral 47 designates a stop member which is threadedly supported in spider 44 for adjustably controlling the limit of travel of plate 43, valve stem 36, and valve 35 in one direction. The stop member depicted in Figure 2 consists of a cylindrical wall 48 and an end wall 49 that is provided with a boss 50 and a central opening 51 concentric with valve stem 36. While the use of the particular stop member described above is recommended, it is to be understood that various other forms of adjustable stops, such as the type illustrated in Figure 3, may be advantageously employed in the practice of my invention.

Referring next to fluid chamber 30, it will be observed that a casting 52 forming the main part of this chamber has a wall 53 that also serves as a wall for valve actuating chamber 29. A conduit 54 is adjustably positioned in wall 53 by virtue of being threadedly supported therein and establishes communication between fluid chamber 30 and valve actuating chamber 29. One end 55 of conduit 54 constitutes a valve seat

for a valve 56 that is carried by a stem 57 which extends through cover plate 31.

A diaphragm motor is formed adjacent the fluid chamber and consists of a casing 89 that is divided by a diaphragm 58 into a pair of compartments, namely, compartment 59 and compartment 60. A relatively small bore conduit 61 places compartment 59 in communication with the back end of the engine cylinder through chamber 21 and ports 22 and 23 in the order set forth. Compartment 60 communicates with the atmosphere through ports 62. Diaphragm 58 carries a pair of plates 63, valve stem 57 being connected to the plate in compartment 60. A compression spring 64, concentric with respect to stem 57, is disposed between cover plate 31 and one of the diaphragm plates for normally urging valve 56 into open position.

A passage 66 and a branch conduit 67 place fluid chamber 30 in communication with conduit 61, while a similar passage 68 and a second branch conduit 69 place valve actuating chamber 29 in communication with conduit 61. Adjustable flow valves 70 and 71 are provided in conduits 67 and 69, respectively. Check valves 72 and 73 in passages 66 and 68, respectively, are shown in enlargement in Figure 4. Each of the check valves consists of a ball check 74 and a compression spring 75 positioned between a valve seat ring 76 and a perforate plate 77 which are threadedly mounted in the passages. By varying the relative position of rings 76 and/or perforate plates 77, the valves may be adjusted to open upon a predetermined fluid pressure to permit fluid flow through the corresponding passages in one direction only. Although I prefer to employ ball check valves in the practice of my invention, it will be obvious that various other types of valves which permit flow only in one direction may be substituted therefor. The pressure at which each check valve will open may be controlled by simply adjusting the corresponding flow valves or by adjusting each check valve and the corresponding flow valve, as desired. It will be noted that valve 72 controls the admission of fluid into fluid chamber 30 through passage 66, whereas valve 73 controls the discharge of fluid from actuating chamber 29 through passage 68.

For the purpose of outlining the mode of operation of the embodiment of the invention illustrated in Figures 1, 2, and 4, it is first assumed that piston 14 is moving in the direction indicated by the arrow on piston rod 15, that is, toward the head end of the cylinder. It will be noted that the piston has completed approximately half of its compression stroke, and that air ports 23 and exhaust ports 24 are all covered by the piston. Starting valve 18 and fuel valve 35 are both closed, as indicated in the drawings, and the fuel and air mixture previously admitted into the cylinder is being compressed preparatory to firing. During this step in the operation, a partial vacuum is created in back of the piston, extending from the back end of the cylinder through air ports 22, air chamber 21, and conduit 61. While the partial vacuum thus created in compartment 59 is generally sufficient to move diaphragm 58 toward the left and thereby move valve 56 to the position shown in Figure 2, the use of compression spring 64 is recommended in order that this movement of the diaphragm and valve 56 may be accomplished in a positive manner. Since the fluid, in this case, air, that was admitted earlier into fluid chamber 30 and transmitted through conduit 54 into actuating cham-

ber 29 is under a higher pressure than the pressure now in conduit 61, it will flow through passage 68, opening check valve 73 and thence be discharged through conduit 69 into conduit 61. Check valve 72 will, of course, remain closed. At the same time, compression spring 45 urges fuel valve 35 into completely closed position and moves diaphragm 46 toward the left until all of the parts of my device have assumed the position illustrated in Figure 2.

As the piston moves in the opposite direction during its expansion stroke it will uncover exhaust ports 24 before air ports 23, allowing the products of combustion to exhaust by way of outlet 25. Air admitted by inlet 19 and valves 20 into chamber 21 is introduced to the head and back ends of the cylinder by ports 23 and 22, respectively. Continued travel of the piston on its expansion stroke compresses the air admitted into the back end of the cylinder and transmits this air under pressure through port 22, chamber 21 and conduit 61. A portion of this air is admitted into compartment 59 of the diaphragm motor, urging diaphragm 58 toward the right against the action of spring 64 and bringing valve 56 into engagement with seat 51 on conduit 54 to thereby form a seal between fluid chamber 30 and actuating chamber 29. Another portion of the fluid flows through branch conduit 67, valve 70, past check valve 72, and thence into fluid chamber 30. Since the fluid pressure in conduit 61 and branch conduit 69 is now superior to that in actuating chamber 29 and passage 68, it will be noted that check valve 73 will remain closed during this step in the procedure.

The various valves will remain in the relative positions indicated in the preceding paragraph until after the engine piston has completed its expansion stroke and has started on its next compression stroke. As the engine piston starts on its next compression stroke, there will be a pressure drop in the back end of the cylinder and in conduit 61 which will allow diaphragm 58 to move valve 56 to open position and permit the fluid previously admitted into fluid chamber 30 to rush into actuating chamber 29 and force diaphragm 46 to the right so as to open fuel valve 35. When an engine cylinder and piston arrangement of the character illustrated in Figure 1 is employed, it is of course desirable that the admission of fuel into the cylinder be delayed until after the exhaust ports are closed during the compression stroke of the piston, thereby eliminating fuel waste which would otherwise occur. It is obvious that the fuel valve may be opened at any predetermined instant during the engine cycle and thus introduce fuel into the cylinder at the most opportune time to obtain maximum benefits and economical operation.

Based on the foregoing, it will be observed that fuel valve 35 remains closed during the entire expansion stroke of the piston and is opened for only a sufficient period during the compression stroke of the piston to admit the required amount of fuel into the head end of the cylinder.

It will be noted that the illustrated embodiments of the invention contemplate the use of a closed system for introducing and withdrawing fluid into and from body member 26. It should be borne in mind, however, that it is not essential to the successful operation of this invention that fluid discharged from actuating chamber 29 be returned to conduit 61. If desired, the portion of branch conduit between valve 71 and conduit 61 may be omitted and the fluid may be

exhausted from actuating chamber 29 direct to the atmosphere.

Reference is next made to Figure 3 wherein like numerals have been used to denote parts that are common to both embodiments of the invention. Only a portion of body member 26 is illustrated herein, as all the other parts are the same as in Figure 2. A casing 78 forms a cylinder 79 within which is a piston 80 that is connected to valve stem 36 and is normally maintained in the illustrated position due to the action of compression spring 45. Piston 80 divides the interior of the casing into a valve actuating chamber 29 and a spring chamber 81, the latter chamber communicating with the atmosphere through an annular space 82 between the casing and valve stem 36. A plurality of threaded members 83 in casing 78 coat with piston 80 to serve as adjustable stops for the piston to thereby restrict the movement of valve 35 in open position. It will be noted that members 83 serve the same function as stop member 47 of Figure 2. A second casing 84 mounted on cover plate 31 forms a cylinder 85 within which is a piston 86 that is connected to valve stem 57 and is normally maintained in the illustrated position due to the action of compression spring 64. Piston 86 divides casing 84 into two compartments, namely, compartment 59 which communicates with the back end of the engine cylinder through conduit 61, and compartment 87 which communicates with the atmosphere through a port 88.

The operation of the second embodiment of the invention is the same as that of the earlier described embodiment. The fluid acts on the pistons to actuate the corresponding valves in the same manner as on the diaphragms illustrated in Figure 2. It will therefore be apparent that equally satisfactory results may be obtained in the practice of my invention by employing diaphragms alone, pistons alone, or a combination of diaphragms and pistons for the actuation of valves 35 and 56, as it is merely a matter of preference and design to determine the arrangement best suited for a particular installation.

From the foregoing it is believed that the construction, operation and advantages of my instant invention will be readily comprehended by persons skilled in the art. It is to be clearly understood, however, that the form of my invention herewith shown and described is to be taken as a preferred example of the same and that various changes in the shape, size and arrangement of parts may be resorted to without departing from the spirit of the invention as defined by the appended claims.

I claim:

1. In a fuel admission device of the character indicated, the combination comprising a fuel valve, a first conduit for supplying fuel to the valve, a fluid chamber, a second conduit independent of the first conduit for supplying a pressure fluid to the fluid chamber, a valve associated with the second conduit for permitting the flow of pressure fluid from the second conduit into the fluid chamber but preventing the withdrawal of pressure fluid therethrough, a valve actuating chamber including a movable partition for co-operating with the fuel valve to actuate the same, means for placing the fluid chamber in communication with the valve actuating chamber, valve means for controlling the flow of pressure fluid through said means, a third conduit independent of the previously mentioned conduits for establishing communication between the valve actuat-

ing chamber and the exterior of the valve actuating chamber, a valve associated with the third conduit for permitting the withdrawal of pressure fluid from the valve actuating chamber but preventing the admission of fluid thereto, a second valve actuating chamber including a movable partition for cooperating with the valve means to actuate the same.

2. In a fuel admission device of the character described, the combination comprising a fuel valve, means for normally maintaining the fuel valve in closed position, adjustable means for limiting movement of the fuel valve in the direction of open position, a first conduit for supplying fuel to the valve, a fluid chamber, a second conduit independent of the first conduit for supplying a pressure fluid to the fluid chamber, a valve associated with the second conduit for permitting the flow of pressure fluid from the second conduit into the fluid chamber but preventing the withdrawal of pressure fluid therethrough, a valve actuating chamber including a diaphragm for cooperating with the fuel valve to actuate the same, means for placing the fluid chamber in communication with the valve actuating chamber, valve means for controlling the flow of pressure fluid through said means, a third conduit independent of the previously mentioned conduits for establishing communication between the valve actuating chamber and the exterior thereof, a valve associated with the third conduit for permitting the withdrawal of pressure fluid from the valve actuating chamber but preventing the admission of fluid thereto, a second valve actuating chamber including a diaphragm for cooperating with the valve means to actuate the same, and means within the second valve actuating chamber for normally maintaining the valve means in open position.

3. In a fuel admission device of the character described, the combination comprising a fuel valve, means for normally maintaining the fuel valve in closed position, adjustable means for limiting movement of the fuel valve in the direction of open position, a first conduit for supplying fuel to the valve, a fluid chamber, a second conduit independent of the first conduit for supplying a pressure fluid to the fluid chamber, a valve associated with the second conduit for permitting the flow of pressure fluid from the second conduit into the fluid chamber but preventing the withdrawal of pressure fluid therethrough, a valve actuating

chamber including a piston for cooperating with the fuel valve to actuate the same, means for placing the fluid chamber in communication with the valve actuating chamber, valve means for controlling the flow of pressure fluid through said means, a third conduit independent of the previously mentioned conduits for establishing communication between the valve actuating chamber and the exterior thereof, a valve associated with the third conduit for permitting the withdrawal of pressure fluid from the valve actuating chamber but preventing the admission of fluid thereto, a second valve actuating chamber including a piston for cooperating with the valve means to actuate the same, and means within the second valve actuating chamber for normally maintaining the valve means in open position.

4. In a fuel admission device of the character described, the combination comprising a fuel valve, means for normally maintaining the fuel valve in closed position, adjustable means for limiting movement of the fuel valve in the direction of open position, a first conduit for supplying fuel to the valve, a fluid chamber, a second conduit independent of the first conduit for supplying a pressure fluid to the fluid chamber, a valve associated with the second conduit for permitting the flow of pressure fluid from the second conduit into the fluid chamber but preventing the withdrawal of pressure fluid therethrough, a valve actuating chamber including a movable partition for cooperating with the fuel valve to actuate the same, means for placing the fluid chamber in communication with the valve actuating chamber, valve means for controlling the flow of pressure fluid through said means, a third conduit independent of the previously mentioned conduits for establishing communication between the valve actuating chamber and the exterior thereof, a valve associated with the third conduit for permitting the withdrawal of pressure fluid from the valve actuating chamber but preventing the admission of fluid thereto, a second valve actuating chamber including a movable partition for cooperating with the valve means to actuate the same, and means within the second valve actuating chamber for normally maintaining the valve means in open position, one of the above mentioned partitions comprising a diaphragm and the other partition comprising a piston.

ARTHUR SANDHOFER.
